UNITED STATES PATENT OFFICE.

GUSTAV HORN, OF BRAUNSCHWEIG, GERMANY; ELISABETH HORN NÉE BELING, LEGAL HEIRESS OF SAID GUSTAV HORN, DECEASED.

RETORT FOR GAS FURNACES.

Application filed September 1, 1921. Serial No. 497,795.

To all whom it may concern:

Be it known that I, GUSTAV HORN, a citizen of the German Republic, residing at 23 Nordstrasse, Braunschweig, Germany, have 5 invented new and useful Improvements in Retorts for Gas Furnaces, of which the following is a specification.

It is well known that the furnaces used for the manufacture of gas are usually 10 equipped with retorts that are made of a solid piece of fire-clay whose cross section is either elliptic or in the form of a segment, or in rare cases quadrilateral with rounded corners. The inside height of these retorts 15 has hitherto been limited to 400 mms. because when this figure was exceeded the retort collapsed. Attempts have been made to overcome this difficulty by making the cross section of the retort in the shape of a D with 20 its arcuate side turned upwards, or in other words by constructing the retort in the shape of an arched tunnel. But even then the same evil occurred whenever the inside height of the arch exceeded 400 mms., especially in cases in which the ordinary large 25 inside breadth of 600 mms. was employed.

Another drawback of these solid retorts is that their length and hence their total capacity is exceedingly limited. On account 30 of the internal stresses due to the gasified coal and in consequence of the strength of the retorts being greatly diminished by the intense heating of the same they have to be furnished in any case with supporting pillars placed inside the furnace at comparatively short distances apart. Now if these supporting pillars yield to different extents, which they very frequently do in consequence of physical differences or of their 35 being subjected to different intensities of heat, the retorts are deprived at one or the other pillar of their proper support and the retort collapses at the particular point in question in the same measure as the pillar 40 gives way. The result of this is that cracks form in the walls of the retort through which a part of the gases in the furnace escape. These escaping gases are burnt at the 45 leaks to no useful purpose. The faulty retort becomes useless prematurely and the furnace has to be put out of commission and the retort replaced.

The object of the invention is to remove all these drawbacks and this is accomplished 50 by constructing the entire retort in a novel

manner, the novel features consisting in making the sole of the retort (which is shaped in the known manner in the form of an arched tunnel) of trough-shaped slabs adapted to overlap each other at their ends, 60 and in erecting a multi-part arched ceiling upon the sole, the parts of the ceiling being composed of long narrow stones each provided at each of their two lateral surfaces, which abut against each other when the stones are joined, with a long continuous channel or groove whose position is such that the grooves of adjacent stones register with each other so that each two abutting neighbouring grooves form a conduit that extends 65 from the one end of the joint to the other. These conduits, which are not in themselves a novel feature in retorts built up of formed stones, are filled with fire-proof mortar. 70

It has been found that in the case of retorts composed in the above-described manner of trough-shaped bottom stones consisting of units whose breadth equals that of the sole of the furnace, and of an arched ceiling constructed of long narrow stones 80 with lateral grooves, the inside height of a retort having a normal inside breadth of 600 mms. may be made 500 mms. or more without the slightest risk of a collapse being incurred. Of course the said increase of the 85 inside height of the retort results in a corresponding increase of its capacity. Even at the figures mentioned this increase is so considerable that in comparison with retorts measuring 600 by 400 mms. the increase of gas production per meter of length 90 of the retort is about 50 cubic meters.

At the same time the enlarged cross section greatly facilitates the operation of knocking the coke out of the retort, and 95 another advantage that accrues is that when the retort becomes defective at any spot it is only necessary to replace the individual shaped stones in question in order to make the furnace perfectly gas-tight 100 again.

The invention is illustrated in the drawing in which—

Fig. 1 shows a cross section of a retort constructed in accordance with the invention. 105

Fig. 2 is a perspective view showing how the shaped stones are built together and

Fig. 3 is a perspective view of a bottom or floor stone.

The sole of the retort is made up of shaped stones *a* of trough-shaped cross section which are as broad as the entire retort and whose length corresponds to that of the long narrow stones *b* used for the arched ceiling or top.

The floor stones *a* Fig. 3 are stepped at the ends that are to be joined to each other in such a manner that although they overlap each other perfectly smooth joints are formed as illustrated in Fig. 2.

The end joints of the shaped stones *b* are staggered as shown in Fig. 2 to the same extent as the floor stones overlap. The shaped stones are all provided at their long lateral abutting surfaces with continuous grooves *c* that register with each other and are filled with fire-proof mortar or fire-clay.

20 The supporting pillars in retorts of this kind are placed at the parts where the ends of the shaped stones abut upon each other.

By constructing the retort of shaped floor stones of equal length and as broad as the entire furnace, and of narrow ceiling stones all of the same length as the floor stones, the result is obtained that whilst the sole of the furnace is very firm and strong, the arched ceiling is rendered so flexible that

it will expand and contract at the various temperatures without serious detriment to its gas retaining capacity. Hence the periods during which such retorts remain operative are lengthened very considerably.

Finally it can be said that the new method of constructing retorts enables them to be made considerably longer than hitherto so that their gas producing capacity is considerably increased.

I claim:

40 A retort for manufacturing gas comprising stepped overlapping trough-shaped floor pieces of the breadth of the whole retort; narrow ceiling pieces each provided at each lateral surface with a groove and placed side by side in groups above the said floor so as to form an arched ceiling, the groups of narrow adjacent ceiling pieces being placed end to end with the ends of the individual pieces displaced to the extent to which the trough-shaped floor pieces overlap, and the grooves in each two abutting lateral surfaces registering with each other so as to form a channel; and fire-proof mortar in each said channel.

45 50 55 In testimony whereof I have signed my name to this specification.

GUSTAV HORN.
